UNITED STATES PATENT OFFICE

2,516,692

FUEL INJECTOR

Louis O. French, Milwaukee, Wis.

Application September 23, 1946, Serial No. 698,834

5 Claims. (Cl. 103—54)

1

The invention relates to automatic fuel injectors of the general type which utilize the compression pressure of the engine to operate a piston which moves relative to a high pressure plunger to produce the injection of fuel into the cylinder of the engine and particularly to an injector in which the stroke of the operating piston and hence the effective stroke of the high pressure fuel plunger is controlled by checking the movement of said operating piston by a checking fluid whose release is controlled by the angular setting of said piston relative to a relief port. One object of this invention is to provide a new and improved means for effecting the angular adjustment of said operating piston over those of my copending applications for Automatic Fuel Injectors, Serial No. 592,675, filed May 8, 1945, and Serial No. 676,952, filed June 15, 1946.

A further object of the invention is to provide an improved and simplified form of automatic fuel injector using a differential needle valve as the injector valve and in which the valve seat and guide are formed in the operating piston to which a sleeve forming a checking piston is secured.

A further object of the invention is to provide an automatic fuel injector in which the operating piston carries a fuel pump chamber and the acceleration of said piston at the beginning of injection is accomplished by a conduit member detachably secured to said piston and having a conical surface engageable with a valve seat on a fixed stop member.

The invention further consists in the several features hereinafter set forth and more particularly defined by claims at the conclusion hereof.

In the drawings:

Fig. 1 is a vertical sectional view of a fuel injector embodying the invention, parts being broken away;

Fig. 1A is a vertical sectional view of an injector showing certain modifications, parts being broken away;

Fig. 2 is a side elevation view of the upper end of the operating piston;

Fig. 3 is a horizontal sectional view taken on the line 3—3 of Fig. 1;

Fig. 4 is an elevation view of the piston rotator;

Fig. 5 is a side elevation view of the upper end of the injector;

Fig. 6 is a view similar to Fig. 1 showing certain modifications, parts being broken away.

Referring to Figs. 1 to 5, the fuel injector in-

2

cludes a housing having a bottom end portion 7, a cylinder 8, and a cap 9, the parts 7 and 8 adapted to be mounted in the head 10 of an internal combustion engine and secured thereto by a threaded connection 11 therewith. The part 7 is a stop member and has an annular valve seat 12. The cylinder 8 has a bore 13 extending therethrough with a shoulder 14 and a threaded portion 15 at its outer end and is provided with a relief and checking fluid supply passage 16, a passage 17 for lubricant or in some instances fuel. The cap 9 has a flanged end seating on the shoulder 14 against which it is clamped by a sleeve nut 18, a guide bore 19, and a valve seat 20 at the inner end of said bore.

An operating piston 21 working in the bore 13 is moved in one direction by the compression pressure of the gases in the combustion chamber C of the engine and in the opposite direction by a spring 22. This piston has a conical end 23 normally seating on the seat 12 to reduce the piston area initially exposed to the compression pressure and thus reduce the required loading of the spring 22 and also permit rapid piston acceleration after said seat is uncovered. It is provided with sealing rings 24, wrench or vise engaging flats 25, an annular groove 26 communicating with passage 17 and is differentially bored to provide an inwardly extending flange 27, a threaded bore 28, and plain bores 29 and 30 forming a shoulder 31.

A conduit member 32 fits the bore 30 with its flanged end abutting against the shoulder 31 and is recessed to receive an apertured valve seat 33 which abuts the end of a pump barrel 34, these parts being clamped together in assembled relation by a hollow wrench-socket-headed screw 35 engaging the bore 28. The conduit member has spray orifices 36 controlled by a normally closed valve 37 which is opened by fuel pressure on the outward or upward movement of piston 21. Any other form of nozzle or discharge valve may be used with piston 21.

The barrel 34 fits the bore 29 and is recessed between its end to provide an annular cooling space 38 which is connected to its interior by inlet ports 39, and in Fig. 1 is connected at its upper end by vertical grooves 40 and radially disposed grooves 41 to the hydraulic chamber 42. Where the fluid used in said checking chamber is a lubricant, then the grooves 40 and 41 are omitted, a compressible gasket inserted in the space 43 and a passage 44, shown in dotted lines in Fig. 1, connects the space 38 with an annular groove 26 in piston 21 which registers with the

passage 17, so that fuel under suitable supply pressure is supplied to said space 38. Thus in one instance the fuel itself may be the checking fluid, and in the other a lubricant is used as a checking fluid.

A high pressure pump plunger 45, working in the barrel 34 controls the ports 39, and after their closure on the outward movement of piston 21 or its movement away from the combustion chamber C, fuel is compressed in the barrel between said plunger and valve 37 until the spring pressure closing said valve is overcome, and then this fuel is discharged into the combustion chamber C through the orifices 36, the amount of fuel depending upon the relative movement of said plunger and barrel 34 or piston 21. To vary this amount the effective stroke of piston 21 is varied by checking more or less of the checking fluid in chamber 42 to stop the movement of said piston. For this purpose piston 21 is provided with a triangular notch providing control edges 47 and 48 which cooperate with the port 16 to cut off said port sooner or later as said piston 21 is moved outwardly by the gases of compression, the particular part of the available stroke period at which this occurs being determined by the angular setting of said edges 47 and 48 relative to said port so as to produce either a complete lapping of this port relative to the control edge 47 with no movement of piston 21 or a lapping of said port after a predetermined movement of said piston.

For adjusting the angular position of control edges 47 and 48 relative to the port 16, a rotatable valve like member 49 mounted in the bore 19 and seating on the seat 20 has depending key projections 50 slidably engaging in key slots 51 in the flange 21 of piston 21. The exposed end of the stem of member 49 has an operating handle 52 slidably keyed thereto and normally secured by a nut 53 against a shoulder on said stem which nut may be loosened to allow inward movement of the valve for priming purposes. The spring 22 engages the head of plunger 45 which in turn abuts the head of member 49, so that the same is normally sealed against the cap 9. By rotation of the member 49 either through the handle 52 or any other suitable turning means, such for example, as a rack and pinion, the piston 21 is moved to the desired position relative to the port 16.

For facilitating setting of the angular position of piston 21 relative to port 16 the operating means for the member 49 is provided with an index pointer 54 cooperating with index markings N, H, and F on the cylinder 8 corresponding to no load, half load, and full load positions of control edge 47 relative to said port, it being noted that the pointer 54 is diametrically opposite the control edge 48 in the full load position of the handle and that as said pointer is angularly shifted toward the right as viewed in Fig. 5 said control edge 47 will finally lap the port 16.

With the above construction the loading of the spring 22 is such that when the compression pressure of the engine has reached a predetermined amount and overcomes this spring loading, the piston 21 is moved outwardly of the combustion chamber C effecting closing of the fuel ports 39, the compression of the fuel in the high pressure pump barrel 34 and its discharge into the combustion chamber C past the valve 37, the amount of fuel injected being dependent upon the angular setting of piston 21 relative to the port 16.

Referring to Fig. 6, a housing is formed of parts 55, 56, and 57 similar to the parts 7, 8, and

9, the part 56 having a relief and checking fluid supply port 58 and a fuel supply passage 59, the cap 57 being secured to the top of cylinder 55 by a nut 60 similar to the nut 18.

5 A piston formed of parts 61 and 62 works in the bore 63 of cylinder 55 is moved outwardly by the compression pressure of the gases in the combustion chamber C of the engine and inwardly into abutting engagement with the stop 10 55 by a spring 64, said piston having a conical end cooperating with the part 55 as in the first described form. The piston part 61 is provided with sealing rings 65, wrench engaging flats 66, an annular groove 67 connecting a port 68 with 15 the passage 59, a threaded outer end 69 of reduced diameter, a valve guide bore 70, a seat 71, and a spray orifice 72. The part 62 is a tubular member having a threaded inner end to fit the end 69 and an inwardly extending flange 73 which is provided with key slots similar to the slots 51 of the first form.

20 A differential pressure operated needle valve 74 has its stem slidably guided in the bore 70 and seats on seat 71 and may have a pintle projection 75 cooperating with the orifice 72 to form an annular fuel spray passage.

25 The stem of valve 74 is provided with a bore 76 connected by passages 77 and 78 with a chamber 79 above the seat 72, and a high pressure 30 pump plunger 80 works in said bore to control a fuel inlet port 81 therein, and is normally held against longitudinal movement by the spring 64 which is interposed between the head of the plunger and the outer end of the stem of valve 73.

35 The part 62 is provided with a V-notch 82 to form control edges similar to the edges 47 and 48 which cooperates with the port 58 in the same way that the port 16 cooperates with said edges to control the amount of checking fluid released from the chamber 83.

40 For angularly adjusting the two-part piston to change the position of said notch 82 relative to said relief port 58, the means shown in the first construction and similarly numbered is used.

45 The construction shown in Fig. 6 embodies specific improvements over that of my application Serial No. 676,952 previously referred to and which earlier filed application contains claims to the common subject matter.

50 In this modified construction when the compression pressure in the engine is sufficient to overcome the loading of the spring 64, the two-part piston 61, 62 is moved outwardly, causing the plunger 80 to lap the ports 81 and compress the fuel in bore 76 and chamber 79 until the pressure acting on the differential area of the valve 74 is sufficient to overcome the spring 64, and then said valve 74 is moved slightly relative to the operating piston and the seat 71 and fuel 55 discharged through the orifice 72 until the notch 82 moves into lapped relation with the port 58, and further movement of the operating piston is stopped by the checking fluid in the chamber 83.

60 The construction shown in Fig. 1A is similar to that of Fig. 1 and operates similarly. The modification resides in forming the conduit member 84 corresponding to the conduit member 32 of Fig. 1 as a clamping nut for holding the valve seat member 33 and the barrel 34 in place, when the barrel is formed as a separate structure, and also for providing a sealing seat 85 cooperating with the seat 12 of the casing part 7, said nozzle having wrench engaging flats 86. The parts 70 33 and 34 associated with the nozzle 84 are 65 clamped together and the barrel 34 clamped

against a shoulder 27 formed in the piston 21, the conduit member 24 having a threaded connection 28 with said piston. With this construction the screw 35 is dispensed with and the conduit member may be removed from the piston 21 without removing said piston from its housing. Also the area of the throttling restriction provided by the surfaces 25 and 12 is reduced over that of Fig. 1 so that the spring 22 does not have to be as heavily loaded.

It is also to be noted that the cap 9 may in some instances be formed as an integral part of the cylinder 8 in which event the nut 18 is eliminated.

Reference is here made to my copending application Serial No. 748,140, filed May 14, 1947, for "Fuel Injector," for any cooling features common to these cases.

I desire it to be understood that this invention is not to be limited to any particular form or arrangement of parts except in so far as such limitations are contained in the claims.

What I claim as my invention is:

1. In an automatic fuel injector in which a high pressure fuel pump of variable stroke is associated with an operating piston movable in response to fluid pressure and provided with control edges, the combination of a cylinder in which said operating piston works with which it forms a checking fluid chamber having a relief port cooperating with the control edges on said piston, and means for angularly adjusting said control edges relative to said port comprising a rotatable member mounted in the outer end of said cylinder in fluid sealed relation with said chamber and operatively connected to said operating piston.

2. In an automatic fuel injector in which a high pressure fuel pump of variable stroke is associated with an operating piston movable in response to fluid pressure and provided with control edges, the combination of a cylinder in which said operating piston works and with which it forms a checking fluid chamber having a relief port cooperating with the control edges on said piston, and means for angularly adjusting said control edges relative to said port comprising a rotatable member mounted in the outer end of said cylinder in fluid sealed relation with said chamber and having a slidably keyed connection with said operating piston.

3. In an automatic fuel injector, the combination with a cylinder having a relief port, of an operating piston movable in said cylinder in response to fluid pressure and provided with a fuel pump chamber having a fuel pressure controlled outlet, said piston and cylinder forming a checking fluid chamber, said piston having control edges cooperating with said relief port to vary the amount of checking fluid released from said checking fluid chamber to vary the stroke of said piston, a plunger for said pump chamber fixed against longitudinal movement, an angularly shiftable member mounted in fluid sealed relation in the outer end of said checking

fluid chamber and having a slidably keyed connection with said operating piston to vary the position of said control edges relative to said port, said plunger abutting said member, and a spring interposed between said piston and plunger for returning said piston, holding said plunger against longitudinal movement and retaining said member in sealed engagement with said cylinder.

10 4. In an automatic fuel injector, the combination with a cylinder having a checking fluid chamber provided with a relief port, of a two-part piston movable in said cylinder in response to fluid pressure, one part of said piston having 15 a discharge passage, a valve seat at the inner end of said passage, and a guide bore, the other part of said piston having control edges cooperating with said relief port to vary the amount of checking fluid released from said chamber, a differential pressure operated needle valve seating on said seat and having a stem slidably mounted in said guide bore and provided with a pump bore communicating with said seat, a high pressure fuel pump plunger working in said pump bore, a fuel port in said stem controlled by said plunger, means for supplying fuel to said port, a spring interposed between said valve and plunger for returning said piston, closing said valve and holding said plunger against longitudinal movement, and means for angularly adjusting said control edges relative to said relief port comprising a rotatable member mounted in the outer end of said cylinder in fluid sealed relation with said chamber and operatively connected to said operating piston.

35 5. In an automatic fuel injector, the combination with a cylinder, of an operating piston movable in said cylinder in response to fluid pressure and provided with control edges and a fuel pump chamber, a valve controlled outlet for said chamber including a valve seat member, a conduit member having threaded connection with said piston, said conduit member having a conical surface, a stop member forming a valve seat cooperating with said surface, a pump plunger working in said pump chamber, said cylinder and piston forming a checking fluid chamber having a relief port cooperating with the control edges on said piston, and means for angularly adjusting said control edges relative to said port comprising a rotatable member mounted in the outer end of said cylinder in fluid sealed relation with said chamber and operatively connected to said operating piston.
